COMBINED COMB AND HAIR DRYER

William D. Smith, P.O. Box 12217,
Oakland, Calif. 94604

Filed Oct. 17, 1972, Ser. No. 300,415

Term of patent 14 years

Int. Cl. D28—03

U.S. Cl. D86—8

FIG. 1

FIG. 2

FIG. 3

FIG. 4

FIG. 5

FIG. 1 is a top plan view of a combined comb and hair dryer showing my new design;

FIG. 2 is a side elevational view;

FIG. 3 is a bottom plan view;

FIG. 4 is a left end elevational view; and

FIG. 5 is a right end elevational view.

I claim:

The ornamental design for a combined comb and hair dryer, as shown and described.
